UNITED STATES PATENT OFFICE.

CHARLES W. DAVIS, OF EDGEWORTH, PENNSYLVANIA, ASSIGNOR TO STANDARD UNDERGROUND CABLE COMPANY, OF PITTSBURGH, PENNSYLVANIA, A CORPORATION OF PENNSYLVANIA.

ELECTRIC FUSE.

1,130,486.

Specification of Letters Patent.

Patented Mar. 2, 1915.

Application filed May 19, 1913. Serial No. 768,597.

To all whom it may concern:

Be it known that I, CHARLES W. DAVIS, residing at Edgeworth, in the county of Allegheny and State of Pennsylvania, a citizen of the United States, have invented or discovered certain new and useful Improvements in Electric Fuses, of which improvements the following is a specification.

My invention relates to fuses or cut-outs adapted to break electric circuits when the current carried thereby becomes abnormal and dangerous, and has particularly to do with fuses for high potential currents.

In fuses for very high potential currents it is desirable, for various reasons, to reduce the length of the fusible element to such dimensions that an arc, upon the blowing of such element, is established between the free ends of the conductor. Various means have been employed to widen the gap between the free ends of the conductor adjoining the fusible element immediately after the fuse has blown, one of such means consisting in providing a casing to surround and inclose the fusible element and the conductors adjoining it, thus confining the explosive forces generated upon the blowing of the fuse and rendering them effective to widen said gap. It has been found that, when the conductor within the casing is submerged in a body of arc-dampening liquid (which of course is relatively non-compressible), the explosive forces acting against such unyielding medium are liable to injure the casing or the box within which it is placed, or to so disturb the general structure as to cause serious inconvenience, it being understood of course that the explosive action of a fuse in a high potential circuit may be of very considerable magnitude.

It is the object of my present invention to provide a fuse of the character particularly described, but wherein the explosive forces of the fusible element will have no prejudicial effect upon the fuse structure.

In the accompanying drawing, which forms part of my specification, I have illustrated a single embodiment of my invention.

Figure 1 is a sectional view of a junction box showing two cables entering therein, the cores of such cables being connected by means of my improved fuse structure, the casing of which is shown in longitudinal section; and Fig. 2 is a sectional view of the fuse casing taken on the line II-II, Fig. 1.

Having reference first to the general construction of the illustrative embodiment of my invention, the cables 1 extend through suitable openings in the bottom of the junction box 2, and are provided with terminal structures 3, there being a pair of spring clips 4 secured to the conductor of each cable. The fuse-inclosing casing 5 of insulating material is secured to brackets 6 of conducting material, which in turn are attached to a frame or handle 7 provided with grooves 8 at its outer ends, such grooves being adapted to engage guide-posts 9, extending from the terminals 3. At the lower ends of the bracket 6 there are knife-blade contacts 10 adapted to be engaged by the spring clips 4.

The means which are particularly shown herein for rendering the expansive forces generated upon the blowing of the fuse effective to widen the gap between the disrupted or fused conductor, consist of the tubular casing 5 having its outer ends closed by means of removable stoppers or closures 11, the conductor within the casing comprising high fusion portions 12 and a central low fusion portion 13. The high fusion portions 12 extend through and are secured one to each closure 11, and electrical continuity is established between the outer ends of such high fusion portions and the brackets 6 by means of flexible conductors 14. As will readily be seen, the expansive forces, generated when the relatively short fusible element 13 blows, will be effective to quickly dislodge the removable closures 11, which will carry with them the higher fusion conductor portions 12, thus widening the gap between their free ends. The arc-dampening liquid, such as oil or carbon tetra-chlorid, in this embodiment of my invention fills, not only the casing 5, but the junction box 2 to a level above such casing as is clearly indicated. In order to permit the liquid to circulate through the casing and thus cool the fusible element 13, the closures 11 may fit loosely in the openings of the casing 5, or small holes 15 may be provided through the walls of the casing.

In order to prevent the explosive forces of the fuse from exerting their effect immediately upon the relatively unyielding body of liquid in the casing, I provide a closed gas-containing chamber above the liquid and adjacent to the fusible element, such chamber

affording a compressible medium for the initial explosive forces, which subsequently become effective to dislodge the closures 11, but with much less violence than if such 5 pressure forces were not permitted to first expand. The gas-containing chamber in the present embodiment of my invention is formed within a supplementary casing 16 clamped to the main casing 5 by means of 10 suitable straps 17, the two said casings forming a two-part single casing, there being an orifice or opening 18 affording communication between said casing parts.

When the fusible element 13 blows, the 15 gases generated thereby, seeking the path of least resistance, escape into and expand within the air chamber. Almost instantaneously the expanded gases exert their force against the body of liquid within the casing 5 and effect, without explosive suddenness, a 20 widening of the gap between the free ends of the conductor portions 12.

I claim as my invention:

1. In an electric fuse, the combination of 25 a fuse casing, a conductor therein comprising a low fusion portion and adjoining high fusion portions, means for rendering the expansive forces generated upon the blowing of said low fusion portion effective 30 to widen the gap formed between the ends of said high fusion portions, a body of arc-dampening liquid in said casing, and a gas-containing chamber above and in communication with the liquid within said casing, 35 the gas within said chamber affording a compressible medium for the initial expansive forces upon the blowing of said low fusion portion of the conductor.

2. In an electric fuse, the combination of 40 a fuse casing, a conductor therein comprising a low fusion portion and adjoining high fusion portions, means for rendering the expansive forces generated upon the blowing of said low fusion portion effective to 45 widen the gap formed between the ends of said high fusion portions, said conductor being submerged in a body of arc-dampening liquid, and a gas-containing chamber adjacent to said low-fusion portion and in 50 communication with the interior of the fuse casing.

3. In an electric fuse, the combination of a tubular open-ended fuse casing, a con-

ductor extending therethrough comprising a central low fusion portion and adjoining 55 high fusion portions, removable closures for the ends of said casing each secured to one of said high fusion conductor portions and removable by the expansive forces generated upon the blowing of said low fusible 60 portion, a body of arc-dampening liquid within said casing, and a gas-containing chamber above the body of liquid within said casing adjacent to said low-fusible portion and in communication with the interior 65 of the fuse casing.

4. The combination with a junction box, a pair of electrical cables entering therein and a conductor extending between the cores of said cables and comprising a low 70 fusion portion and adjoining high fusion portions; of a fuse casing inclosing said conductor, means for rendering the expansive forces generated upon the blowing of said low fusion portion effective to widen 75 the gap formed between the ends of said high fusion portion, a body of arc-dampening fluid within said junction box and within the casing surrounding the fuse, and a gas-containing chamber above and in communication with the liquid within said 80 casing, the gas within said chamber affording a compressible medium for the initial expansive forces generated by the blowing of said low fusion conductor portion. 85

5. In an electric circuit opener, the combination of a pair of electrically united conducting elements adapted when separated to break an electric circuit and movable with relation to each other when thus separated, 90 an arc-dampening fluid surrounding the point of connection of said conductors, and a member forming a gas-containing chamber being in communication with the interior of the fuse casing and adjacent to said 95 point of connection, the gas in said chamber affording a compressible medium for the initial expansive force effected by the arc formed upon the separation of said conductors. 100

In testimony whereof I have hereunto set my hand.

CHARLES W. DAVIS.
